US00D724443S

(12) **United States Design Patent** (10) **Patent No.:** **US D724,443 S**
Sharpe et al. (45) **Date of Patent:** **** Mar. 17, 2015**

(54) **CONTAINER**

- (71) Applicant: **Glaxo Group Limited**, Brentford, Middlesex (GB)
- (72) Inventors: **Tim Sharpe**, Warwick (GB); **Jonathan Stewart**, Warwick (GB); **Stuart Cole**, Warwick (GB)
- (73) Assignee: **Glaxo Group Limited**, Brentford, Middlesex (GB)
- (**) Term: **14 Years**
- (21) Appl. No.: **29/471,975**
- (22) Filed: **Nov. 7, 2013**

(30) **Foreign Application Priority Data**

- May 22, 2013 (GB) 4030028
- (51) **LOC (10) Cl.** **09-05**
- (52) **U.S. Cl.** **D9/710**
- USPC **D9/702-714, 720-722, 414, 430-435, D9/696, 716, 771, 447, 522, 571-575, 682, D9/738-747, 516-517, 529-530, 547-549, D9/569, 537-538, 544, 503-505, 545, 440, D9/442; 383/6, 9, 22, 61.1, 96, 80-81, 383/104, 901, 63, 203, 107, 119, 120, 123, 383/42, 906, 93; D7/213, 601-602; 222/92, 222/104, 107, 206; 604/408, 410, 403; 220/495.03, 669, 675; 215/381-385, 215/12.1, 400, 316, 328**
